[57] **CLAIM**

The ornamental design for a binder cover, as shown.

DESCRIPTION

FIG. 1 is a front perspective view of a binder cover showing my new design;

FIG. 2 is a front elevational view thereof, with the flap in open condition;

FIG. 3 is a rear elevational view thereof, with the flap in closed condition;

FIG. 4 is a left end elevational view thereof, the right end being as shown in FIG. 1; and

FIG. 5 is a bottom plan view thereof, the top being substantially the same.

The inside of the binder cover is plain and unornamented. The broken lines are for illustrative purposes only, forming no part of the claimed design.
